FRED WILKIE, OF NEWARK, NEW JERSEY.

MACHINE FOR MAKING FLEXIBLE TUBING.

964,595.

Specification of Letters Patent. Patented July 19, 1910.

Application filed December 14, 1909. Serial No. 532,983.

To all whom it may concern:

Be it known that I, FRED WILKIE, a citizen of the United States, residing at Newark, in the county of Essex and State of New Jersey, have invented certain new and useful Improvements in Machines for Making Flexible Tubing; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a machine for making tubular structures of strips of material, particularly flexible tubing made up of a strip of metal, the strip being wound upon itself to form a helix and being of a formation having its edges interlocked on the abutting edges of the convolutions of the helix.

The invention is further designed to provide a structure having a mandrel on which the tubing is wound and having co-acting rollers and guiding plates so that the strip of material is properly fed and caused to engage the next succeeding convolution, whereby the parts are closely interlocked.

The invention is also designed to provide a frictional connection between the driving means and the rollers and guiding plates and also the mandrel to cause a pull on the strip of material being fed to the device, and permit a slipping when the pull on the device exceeds the rate of the feed.

The invention is illustrated in the accompanying drawing, in which—

Figure 1 is a face view of the device. Fig. 2 is a side view thereof. Fig. 3 is a section illustrating the fitting together of the convolutions of the helix and showing one of the feed rolls engaging the same. Fig. 4 is a section of one of the guide plates, and Fig. 5 is a detail of the connection between the driving shaft and the driving means for the feed rolls.

The device consists of a face plate 10 which is secured to a bearing 11 in which is mounted the mandrel 12, which mandrel forms the element on which the flexible tubing is wound. The face plate 10 has arranged therein the adjustable boxes 13 which are adjusted by means of the screws 14 to vary the distance of the boxes from the man-

drel, and correspondingly the distance of the rolls 15 from the mandrel. These rolls 15 are mounted on a shaft 16, the shaft in each case passing through the boxes 13 and 60 being positively driven by means of the device herein described. The feed rolls 15 are placed circumferentially around the mandrel so as to bear on the S-shaped strip of material 17 which is wound in the form of a 65 helix to form the tubing. In forming the helix the strip of material passes around the mandrel at a pitch that is according to the width of the strip and its engaging portions. The rollers 15 are arranged to coincide with 70 this pitch so that each successive roller is a little farther advanced from the face plate so that the flange 18 on each roll will engage the portion 19 of the strip 17, and the flat face 20 of each roll will engage the flat portion 21 of the strip 17 to force the adjacent edges of the strip to interlock; the flange 18 of each roll pressing the portion 19 firmly and tightly down against the edge of the next preceding convolution so that the parts 80 will have no slide longitudinal of the flexible tube being formed. The rolls are thus arranged at an obtuse angle to the axis of the mandrel. Between the feed rolls are the guiding blocks 22 which are also arranged 85 according to the pitch of the convolutions of the helix, this pitch being preferably supplied by mounting the guiding plates on a ring 23 which fits against the face plate 10 and is cut with its face 24 at the same pitch 90 as the convolutions of the tube being formed. Each guide plate, on its face toward the mandrel, is provided with a hook 25, which hook is turned toward the face plate and is designed to engage the outer turned over 95 portion of the edge 26 of the strip of material 17 being fed to the machine, as shown more particularly in Fig. 4. The hooks 25 act to overcome any tendency of the flanges 18 of the rollers to crowd the convolutions 100 or the strip of material, and maintain each convolution at the same width. The rollers 15 and their shafts 16 are connected, by any usual flexible shafting 27, with the shafts 28 which pass through the boxes 29 in the 105 rear plate 30, which boxes are adjustable by means of the screws 31. On each of the shafts 28 is mounted a gear-wheel 32, these gear-wheels surrounding and all being in mesh with a gear 33 mounted on the shaft 34 which is a continuation of or integral 110 with the mandrel 12. This gear connection

insures all the rollers 15 and their shafts rotating in the same direction to feed the material to the mandrel, and the flexible shafting, or the flexible connections in the 5 shafting, permits both the adjustment of the roll forward and from the mandrel, and also the arrangement of the rolls 15 at an angle to the axis of the mandrel, and therefore at an angle to the axis of the tube being 10 formed.

This machine is adapted for use in connection with any of the well known machines for forming the metal into the S-shaped strip, the device herein illustrated 15 being driven either from the machine for forming the strip, or from an independent source of power. In Fig. 1, I illustrate rollers 35 for the purpose of showing conventional means for feeding the strip 17 to the machine for forming the tubes, and the mandrel 12 and the rollers 15 are driven at a speed to keep the strip 17 taut to make it feed into the convolution without danger of its becoming misplaced. If the feed of 20 the mandrel 12, and therefore of the rolls 15, exceeds the feed of the rollers 35, the strip 17 will be severed, and to overcome this I install a frictional drive for the shaft 34, this frictional drive being of any well 25 known form, but I prefer to use the one illustrated in Fig. 2 consisting of parallel plates 36 secured to the shaft 34 and flanking a sprocket or similar driven element 37, the sprocket having, between its sides and 30 adjacent faces of the flanges 36, leather or any other suitable plates or washers 38 which serve to transmit the motion from the sprocket to the plates and thereby to the shaft, but when the strain on the strip 17, 35 if the feed is too fast, exceeds the speed of the rollers 35, the sprocket will slip between the washers 38, and in this way danger of breaking the strip 17 is overcome.

Having thus described my invention, what 40 I claim is:—

1. A machine for making flexible tubing comprising a mandrel adapted to rotate, rolls arranged at an obtuse angle to the axis of the mandrel and adjacent to the mandrel, 45 and blocks having hook-shaped portions adapted to engage the material being wound, the hook-shaped portions of the blocks being arranged at the same angle to the axis of the mandrel as the rolls.

2. A machine for forming flexible tubing comprising a mandrel adapted to rotate, rolls adapted to engage a strip being wound on the mandrel, means for driving the rolls from the mandrel, and guide blocks arranged at the same angle as the rolls and between the rolls, the blocks having hooks to engage the strip on the mandrel.

3. A machine for making flexible tubing comprising a mandrel adapted to be rotated, rolls arranged adjacent to the mandrel 55 and adapted to engage material wound on the mandrel, each roll having a flange thereon, guiding blocks having hook-shaped portions adjacent to the mandrel and adapted to engage the material being wound, the hook-shaped portions of the blocks being arranged at an obtuse angle to the axis of the mandrel, means for adjusting the rolls toward and from the mandrel, and means for driving the rolls. 75

4. A machine for making flexible tubing comprising a bearing having a mandrel mounted therein, a face plate, boxes arranged to slide in the face plate, rolls rotatably mounted on the boxes, the rolls being 80 arranged at an obtuse angle to the axis of the mandrel, a gear on the mandrel, a back plate, gears mounted on the back plate and in mesh with the gear on the mandrel, a flexible connection between each gear on the 85 back plate and a roll, means for driving the mandrel, and guide blocks secured to the face plate and having hook-shaped portions thereon arranged at the same angle to the axis of the mandrel as the rolls. 90

5. A machine for making flexible tubing comprising a bearing having a mandrel mounted therein, a face plate, rolls arranged at an obtuse angle to the axis of the mandrel, means for adjustably securing the rolls on the 95 face plate, a ring arranged in the face plate around the mandrel, the ring being formed with a surface that is helical and has the same pitch as the material being wound on the mandrel, blocks on the face of the ring 100 and having hook-shaped portions to engage the material to be wound on the mandrel, an operative connection between the mandrel and the rolls, and means for driving the mandrel.

6. A machine for making flexible tubing 105 comprising a mandrel adapted to rotate, rolls arranged at an obtuse angle to the axis of the mandrel and adjacent to the mandrel, and blocks having portions to engage and guide the material to be wound on the mandrel to form the tubing, the blocks being so disposed that they engage the material between the rolls, the portions of the blocks for engaging the material being arranged at the same angle to the axis of the mandrel as 110 the rolls.

In testimony, that I claim the foregoing, I have hereunto set my hand this 13th day of December 1909.

FRED WILKIE.
